(57) **CLAIM**

The ornamental design for a LED lamp, as shown and described.

DESCRIPTION

FIG. 1 is a front, right, and top perspective view of a LED lamp, showing my design.

FIG. 2 is a rear, left, and bottom perspective view thereof.

FIG. 3 is a right side elevation view thereof.

FIG. 4 is a left side elevation view thereof.

FIG. 5 is a top plan view thereof.

FIG. 6 is a bottom plan view thereof.

FIG. 7 is a front elevation view thereof.

FIG. 8 is a rear elevation view thereof.

FIG. 9 is a partial enlarged view of an area labeled 9 in FIG. 1; and,

FIG. 10 is a partial enlarged view of an area labeled 10 in FIG. 1.

The evenly spaced broken lines shown in the drawings are included for the purpose of illustrating portions of the LED lamp that form no part of the claimed design. The unevenly spaced broken lines in FIGS. 1, 9 and 10 indicate the outer limits of areas shown enlarged and form no part of the claimed design.

The drawings contain symbolic break lines in FIGS. 1-4 and 7-8. The portion between the break lines forms no part of the claimed design.
